[57] CLAIM

The ornamental design for a goblet or similar article, as shown and described.

DESCRIPTION

FIG. 1 is a view in perspective of a goblet or similar article showing my new design in the size and proportions of a juice glass;

FIG. 2 is an elevational view thereof;

FIG. 3 is a top plan view thereof;

FIG. 4 is a bottom plan view thereof;

FIG. 5 is an elevational view of a goblet or similar article showing my new design in the size and proportions of a water glass;

FIG. 6 is a cross-sectional view taken on line 6—6 of FIG. 5;

FIG. 7 is a view in perspective of a goblet or similar article showing my new design in the size and proportions of a wine glass;

FIG. 8 is an elevational view of the goblet of FIG. 7;

FIG. 9 is a top plan view thereof;

FIG. 10 is a bottom plan view thereof;

FIG. 11 is an elevational view of a goblet or similar article showing my new design in the size and proportions of an on-the-rocks style glass;

FIG. 12 is an elevational view of a goblet or similar article showing my new design in the size and proportions of another on-the-rocks style glass.
